(57) **CLAIM**

The ornamental design for a task chair, as shown and described.

DESCRIPTION

FIG. 1 is a front elevation view of a task chair incorporating my new design;

FIG. 2 is a rear elevation view thereof;

FIG. 3 is a left side elevation view thereof, the right side elevation view being a mirror image; and,

FIG. 4 is a bottom plan view thereof.

The broken lines shown are for illustrative purposes only and form no part of the claimed design.

1 Claim, 2 Drawing Sheets

FIG. 1

FIG. 2
